UNITED STATES PATENT OFFICE.

DANIEL DRAWBAUGH, OF EBERLY'S MILL, PENNSYLVANIA.

TELEPHONE.

SPECIFICATION forming part of Letters Patent No. 290,978, dated December 25, 1883.

Application filed June 20, 1883. (No model.)

To all whom it may concern:

Be it known that I, DANIEL DRAWBAUGH, of Eberly's Mill, Cumberland county, Pennsylvania, have invented new and useful Improvements in Telephones, of which the following is a specification.

The invention relates to a magneto-telephone of the class commonly used as receiving-instruments; and it consists in the construction 10 herein set forth, whereby one of the pole-pieces of the permanent magnet constitutes the core of the electro-magnet. The other pole-piece of opposite polarity is substantially in the form of a cylinder encircling the electro-magnet, the coil of which is rigidly fixed between 15 said pole-pieces. The diaphragm is of inductive material, and is not polarized. This construction I have found materially conduces to 20 loudness of sound emitted and clearness of articulation.

In the accompanying drawings, Figure 1 is a face view of the instrument with the mouth-piece removed and part of the diaphragm broken away. Fig. 2 is a vertical section on 25 the line *x x* of Fig. 1. Fig. 3 is a transverse section on the line *y y* of Fig. 1. Fig. 4 shows the cylindrical pole-piece detached.

Similar letters of reference indicate like parts.

30 A is the body of the instrument; B, the mouth-piece; C, a diaphragm of inductive material, secured between said mouth-piece B and body A, and having interposed between its rear side and the body a gasket or washer, D, 35 of paper or rubber.

E is the permanent magnet, secured to the body by the screws F. One pole of the magnet E terminates in a bar, G. Said bar may be formed of the material of the magnet itself, 40 and be a prolongation thereof; or it may be a separate piece, as shown, secured to the magnet by a screw-thread, or in any other convenient way. The bar G constitutes the core of the helix or coil of insulated wire H. The 45 spool or bobbin I of this helix has its rear flange, J, larger than its front flange, K.

L, Fig. 4, is a circularly-curved or substan-

tially cylindrical piece of inductive metal, which surrounds the coil H and front flange, K, of the spool I, its rear edge abutting against 50 the flange J of said spool. A portion of the flange J is cut away to allow of the passage through of an offset or projection, M, of the pole-piece L. Said projection is in contact with one pole of the permanent magnet E on the outside of the instrument, as shown in Fig. 2. The spool I is thus rigidly held between the pole-piece L, which may fit tightly in the body A and the magnet E. By this construction both poles of the permanent magnet are 55 presented to the diaphragm, and their arrangement is such as to form a magnetic field of considerable intensity. The diaphragm is not polarized.

I claim as my invention—

1. The combination, in a telephone, of a non-polarized diaphragm of inductive material, a permanent magnet having one of its poles terminating in a bar or core and the other terminating substantially in a ring or cylinder, and a fixed helix carried by the core and located within the ring or cylinder, substantially as described.

2. In a telephone, a permanent magnet forming a handle for the instrument, and carrying 75 at one extremity the core and at the other the tubular or cylindrical extension, in combination with the flanged spool containing the helix, one of said flanges being fitted to and supported within the tubular extension, while the other flange rests against the end of the latter, whereby the several parts are fixed and retained in proper relative position for co-operation with the diaphragm, substantially as 80 described.

3. In a telephone, the case A, supporting the diaphragm, the permanent magnet E, adjustable core G, and cylindrical extension L, in combination with the spool I, having the flanges K J, as and for the purpose set forth. 90

DANIEL DRAWBAUGH.
